(57) **CLAIM**

The ornamental design for a wine rack, as shown and described.

DESCRIPTION

FIG. 1 is a perspective view of a wine rack, showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a perspective view of the wine rack, shown in use. The broken lines showing a bottle of wine in FIG. 8 depicts environmental subject matter that forms no part of the claimed design.
